EXTENSION TABLE WITH CENTER
ELEVATING LEAFEarl C. Booth, Columbus, Ind., assignor to
Noblitt-Sparks Industries, Inc., Columbus, Ind.,
a corporation of Indiana

Application December 21, 1946, Serial No. 717,649

3 Claims. (Cl. 311—47)

1

This invention relates to extension tables and more particularly to an extension table embodying a center leaf which can be inserted when desired between two relatively movable sections of the table-top. It is an object of this invention to facilitate the insertion, removal, and storage of the center leaf of an extension table. Another object of the invention is to provide a metal extension table which will be of attractive appearance and which will embody a center leaf that can readily be brought into operative position from a concealed position beneath the table top.

In carrying out my invention, I provide a table top divided into two halves and interconnected for longitudinal sliding movement by means of tubular guide rods. Mounted for swinging movement about the respective axes of the guide rods are a pair of cams which support a center leaf and which, by their rotation, are adapted to move the center leaf between a position co-planar with the halves of the table-top and a position beneath the top. The two halves of the table top are provided with depending peripheral flanges which serve to conceal the center leaf when it is in its lower position. The center leaf is provided at its ends with pivotally mounted skirt-portions which conform in cross-sectional shape to the peripheral flanges on the top-sections. The skirt portions are swingable about their axes of pivotal mounting on the center leaf between positions beneath the center leaf and positions generally normal to the center leaf; and at least one of the skirt portions is connected to the aforesaid cams to cause them to rotate to elevate the center leaf as the skirt portion is swung outwardly and downwardly. The parts are so constructed and arranged that when the skirt portions reach positions normal to the center leaf the center leaf will have been raised to the plane of the top and the skirt portions will be substantially flush with the peripheral flanges on the top.

The accompanying drawings illustrate my invention. Figs. 1 and 2 are respectively a top-plan and a side elevation of an extension table showing the center leaf in place; Fig. 3 is a fragmental top plan view similar to Fig. 1 but on a larger scale; Fig. 4 is a transverse vertical section on the line 4—4 of Fig. 3 showing the center leaf in its elevated position; Fig. 5 is a section similar to Fig. 4 showing the center leaf depressed; Fig. 6 is a fragmental vertical section through one end of the center leaf; Figs. 7 and 8 are longitudinal vertical sections on the lines 7—7 and 8—8 of Figs. 4 and 5 respectively; and Fig. 9 is a fragmental side elevation of the table-top with por-

2

tions thereof broken away and illustrated in section.

The table illustrated in the drawings comprises a pair of complementary top-sections 10 and 11 each provided at its outer corners with supporting legs 12. Each section of the top has a downwardly projecting flange 13 extending, preferably continuously, along its sides and across its outer end. For a purpose which will hereinafter become apparent, each of the flanges 13 has an outwardly offset portion 14 the lower edge of which is secured to a U-shaped tubular element 15.

Extending across and beneath the top-sections 10 and 11 are transverse partitions 20 provided with aligned openings which slidably receive two laterally spaced, parallel guide rods 21. The two sections of the table are slidably interconnected by the guide rods 21 for relative movement between a position in which the inner ends of the top-sections are in abutting relation and a position in which such inner ends are separated to permit the insertion of a center leaf 22 between them. Desirably, the inner end of each of the top-sections is bent downwardly to provide a stiffening and reinforcing flange 23.

The center leaf 22 has a length equal to the width of the top-sections 10 and 11, and is provided along its sides with stiffening flanges 24 adapted to abut against the flanges 23 on the top section when the center leaf is in operative position. At its ends, the center leaf has downwardly projecting flanges 25 (Fig. 6) which conform in cross-sectional shape and extent to the unoffset portions of the flanges 13 on the top-sections 10 and 11. Secured to the under surface of the leaf 22 adjacent each end thereof is a bracket 27 which conveniently extends for substantially the full width of the leaf and to which there is pivotally secured a skirt 28. Conveniently, the pivotal mounting of the skirt 28 on the bracket 27 is effected through a hinge 29 of the piano type. Each of the skirts 28 is swingable between a position, shown in Fig. 5, in which it lies beneath the center leaf to a position, shown in Figs. 4 and 6, in which it extends downwardly generally normal to the center leaf. That portion of the skirt 28 which is visible beneath the flange 25 when the skirt is in the latter position is shaped to conform to the offset portions 14 of the flanges 13 on the top-sections 10 and 11; and a tube 31, conforming to the tubes 15, is secured to the outer edge of the skirt, as by means of screws 32.

The innermost transverse ribs 20 are spaced outwardly from the inner ends of the top-sections

10 and 11 to provide for the reception of the center leaf 22 between them when the table is collapsed, as indicated in Fig. 8. Mounted on each of the guide rods 21 between the ribs 20 is a cam 35 having two generally plane portions 36 and 37 which extend parallel to the axis of the associated tube 21 but are spaced at different distances from such axis and which are interconnected by a smoothly curved portion 38. Conveniently, each cam is formed as a sheet-metal stamping to provide the portions 36, 37, and 38 and also to provide end walls 39 having aligned openings which rotatably receive the tubes 21.

The two cams 35 provide a support for the center leaf 22. Each cam is rotatable through approximately 90° between a position in which its surface 36 is uppermost to support the center leaf in its depressed position and a position in which its surface 37 is uppermost to support the center leaf in elevated position. For the purpose of effecting joint rotation of the cams, they may conveniently be interconnected by links 40, as indicated in Figs. 4 and 5. As there shown, the cams 35 swing in opposite directions about their respective axes, and the links 40 are accordingly crossed. It is to be understood, however, that the cams need not swing in opposite directions and that means other than links 40 may be employed to interconnect them.

Conveniently, the cams 35 are arranged for rotation by movement of one or the other, or both, of the skirts 28. As shown, each of the skirts 28 is connected to its adjacent cam 35 through a link 42, the arrangement being such that when the skirt is swung downwardly and outwardly from the position beneath the center leaf the cams 35 will be rotated to elevate the center leaf, and vice versa.

To maintain the two cams 35 opposite each other and also to provide an additional guide for the tubes 21, I may employ the means shown in Figs. 3 and 4. Such means comprises collars 45 which are slidably mounted on the guide tubes 21 inside the end walls 39 of the cams 35. The two collars on each guide rod are held in proper spaced relation by struts 46, and opposite collars are interconnected by struts 47. Stiffness for the structure is provided by diagonal braces 48.

The condition existing when the table is collapsed is illustrated in Figs. 5 and 8. In that condition, the skirts 28 are swung inwardly to generally horizontal positions, and the cams 35 are disposed with their surfaces 36 uppermost to support the center leaf 22 in a depressed position such that the flanges 23 on the top-sections 10 and 11 will clear the leaf and permit the two top-sections to be moved toward each other until the flanges 23 abut, as shown in Fig. 8. In this position of the leaf, it is located below the unoffset flange-portions 13 and concealed by the offset flange-portions 14, which are spaced outwardly from the ends of the leaf and serve to conceal it.

When it is desired to extend the table, the two sections thereof are drawn apart to the limit permitted by abutments 21' on the guide rods 20, thus creating between the flanges 23 a space into which the center leaf 22 may be elevated. If necessary, the center leaf is moved along the rods 21 to a position under such space, and one of the skirts 28 is then swung outwardly and downwardly from the position indicated in Fig. 5 to the position shown in Fig. 4. Because the skirts are interconnected with the cams by the links 42 while the cams are interconnected by the links 40, such downward and outward swinging move-

ment of either skirt rotates the cams and the other skirt until the cam-portions 37 are uppermost, thus raising the center leaf into the plane of the top-sections 10 and 11. In this condition, the skirts 28 lie flush with the offset flange-portion 14 and the tubes 31 are in alignment with the tubes 15.

In both the elevated and depressed positions of the leaf 22 its interconnection with the cams 35, through the skirts 28 and links 42, maintains it substantially centered transversely of the table. This insures that the top sections and flanges 13-14 will clear the center leaf when the two sections of the table are forced together following depression of the center leaf. If it is desired to improve the alignment of the elevated leaf 22 and the skirts 28 with the top sections 10 and 11 and the flanges 13-14, the skirts and flanges may be provided with interfitting, aligning provisions. This may conveniently be done, as indicated in Fig. 9, by providing one of the tubes 15 at each side of the table with a co-axial projection 45' adapted to be telescopically received in the adjacent end of the tube 31 and by providing the opposite end of the tube 31 with a co-axial projection 31' adapted to be similarly received in the end of the other tube 15. When the leaf 22 is depressed and the table collapsed, each projection 45' will enter the adjacent end of the other tube 15 to locate relatively to each other the two top-sections 10 and 11 and the flanges 13-14 respectively thereon.

I claim as my invention:

1. An extension table, comprising two complementary top sections each provided with supporting legs, parallel guide rods located below the top-sections and interconnecting them for longitudinal movement toward and away from each other, an extension leaf for insertion between said top-sections, means including cams rotatably supported from said guide rods for raising and lowering said extension leaf into and out of the plane of said top-sections, said guide rods being of circular cross-section and said cams having circular openings rotatably receiving said rods, and an operating member for rotating said cams.

2. An extension table, comprising two complementary, sheet-metal top-sections each provided with supporting legs, parallel guide rods located beneath said top-sections and interconnecting them for longitudinal movement toward and away from each other, a sheet-metal extension leaf for insertion between said top-sections, means for supporting said extension leaf alternatively in an elevated position co-planar with said top sections or in a depressed position beneath said top-sections, each of said top-sections being provided with flanges having upper portions extending downwardly from the side-edges of the top sections and lower portions which are offset outwardly relative to the upper portions and beyond the side-edges of the top sections far enough to clear the ends of the extension leaf when it is in depressed position and the top-sections are moved together, said extension leaf being provided at its ends with downwardly projecting integral flanges flush with the upper flange-portions of the top sections when the leaf is in its elevated position, skirts pivotally mounted on said leaf adjacent the ends thereof and swingable between first positions beneath the leaf and second positions in which they extend outwardly and downwardly beyond the flanges on the leaf and are flush with the offset portions of the flanges on the top-sections.

3. The invention set forth in claim 2 with the addition of operative connections between said skirts and said leaf-supporting means, said leaf-supporting means being operative to raise said leaf from depressed to elevated position as said skirts are swung from said first positions to second positions.

EARL C. BOOTH.
